THERMOSTATIC ALARM

Frank H. Pietzsch, Coupland, Tex.

Application July 26, 1932. Serial No. 624,824

4 Claims. (Cl. 116—103)

This invention relates to an improved thermostatically controlled alarm.

An important object of my invention is to provide a simple, economical and dependable thermostatically controlled audible alarm usable in a room or other enclosure to warn of abnormal heat conditions.

Another important object of my invention is to provide a device of the character described which is capable of being modified to act efficiently as a practical and efficient fire alarm or as a temperature indicator for use in a sick room, or nursery.

In the accompanying drawings there is shown a preferred embodiment of the invention;

Figure 1 is a front elevational view of the embodiment of the invention.

Figure 2 is a side elevational view of Figure 1.

Figure 3 is a vertical longitudinal sectional view through Figure 1 disclosing interior mechanism.

Figure 4 is a horizontal sectional view taken through the lower part of Figure 1 and looking downwardly.

Figure 5 is a vertical transverse sectional view through Figure 5 looking toward the left.

Referring to the drawings in detail, wherein like numerals refer to like parts through the same, the numeral 6 designates generally a supporting medium comprising the open-ended box portion 7 from the top of which rises the standard portion 8 on the front face of which is secured the alarm mechanism housing 9.

The box portion 7 and the standard portion 8 are composed by sheet metal members 10, 11. The sheet metal member 10 comprises the L-shaped portion 12 having the right angular, short vertical flange 13. The sheet metal member 11 comprises the horizontal bottom portion 14 having at its front end the short vertical flange 15 bolted as indicated at 15 to the back of the vertical front portion of the member 10, and the vertical back portion 17 having the short horizontal portion 18 which has the tall vertical plate 19, to the front of which is bolted as indicated at 20, the short vertical flange 13. The numerals 21 designate similar brackets bolted or riveted as indicated at 21' to the underside of the horizontal bottom portion 14 for supporting the bottom spacedly from a supporting medium 22.

A cylindrical housing 23 is secured by its flange 24 to the front face of the plate 19 by means of bolts 25. Surrounding the front of the housing 23 and spaced therefrom is the shell 26 constituting an alarm bell. It is attached by screws 27 to

structure of the housing 23 and has an opening 28 in its front wall.

Within the box portion 7 is a multiple wafer type thermostat unit 29 which is mounted on the bottom 14 by a bolt or binding post 30 which passes therethrough and has a nut 31 thereon operable for clamping an electrical conductor between it and the bottom 14. A washer 32 separates the thermostat unit 9 from the bottom 14. On the top element of the thermostat unit 9 is a contact 33 in circuit with the binding post 30. The box portion 7 acts as a shelter for the thermostat against vagrant currents of air, which might be alternately cool and hot, and functions to confine about the thermostat the heated air which enters the open ends of the box portion and which is in point of temperature, representative of the temperature of the air in the place in which the device is located, so that the thermostat is conditioned to operate on a mean level of high temperature in the place in which it is located.

The alarm mechanism comprises the spring motor driven gear wheel 34 which is suitably mounted on shaft 35 within the housing 23. The wheel 34 is in mesh with a small pinion 36 fixed for rotating an escapement wheel 37. Rockably mounted at 38 is the inverted J-shaped bell hammer operating member 39 which has within its crook the spaced dogs 40 for cooperating with the teeth of the escapement wheel 37. Pivotedly connected to the lower end of the member 39 as indicated at 41 is one end of the link 42 whose other end is pivotally connected as indicated at 43 to an intermediate portion of the bell hammer 44. The bell hammer 44 is pivotally mounted at its lower end as indicated at 45 and has on its upper end the hammer head 46 which operates through an opening 47 in the side of the housing 23 for striking the bell 26.

Pivotally mounted as indicated at 48 is an L-shaped latch member 49 whose upper end is formed to hook over a portion of the member 39 indicated by the numeral 50, to hold the member 39 in a position in which the bell hammer 44 is withdrawn from the opening 47 and held inoperative. Means for releasing the latch 49 from the member 39 so as to permit the member 39 to be moved by the escapement wheel 40 for operating the hammer 44, comprises the vertically movable rod 51 whose upper end is pivotally connected as indicated at 52 to the free end of the foot portion of the L-shaped latch 49 and which carries on its lower end, means to be engaged and moved upwardly by the thermostat unit as it expands. A leaf spring 53 is mounted on one side of the hous- 110

ing 23 and presses upon the upper side of a lug 54 on the latch for holding the latch normally engaged with the member 39 in the manner shown in Figure 3. The rod 51 passes through the wall 5 of the housing 23 and through the top of the box portion 7 in axial alignment with the contact head 33 of the thermostat unit. An opening 55 in the top of the box portion is of sufficient size to enable a head 57 on the lower end of the rod to move freely therethrough when pushed upwardly by the expansion of the thermostat unit. Between the head 57 and the wall of the housing 23, there is circumscribed upon the rod 51 a return spring which normally forces the rod 51 downwardly and assists the leaf spring 53 in holding the escapement mechanism inoperative. The head 57 is in the nature of a binding post for connecting a conductor, and carries adjustable contact point 58, to be electrically engaged by contact head 33 of the thermostat, when the thermostat expands, for closing an electrical alarm circuit (not shown).

When the thermostat expands upwardly and engages the contact point 58 and pushes the rod 51 upwardly, the alarm circuit is closed and the latch 49 rocked on its pivot 48 in a direction to disengage it from the member 39, whereby the member 39 is freed to be rocked to and fro by the escapement wheel 37 and ring the bell 26 with the hammer 44. When the thermostat contracts again, the spring 56 will push the rod 51 downwardly into its initial position assisted by the leaf spring 53. This action re-engages the latch with the member 39 and resets the alarm.

It is evident that the structure is electromechanical in nature in that it permits the actuation of an electrical alarm at a remote place simultaneously with the operation of the local mechanical alarm.

As before stated, the invention may be used as a fire alarm or may be used as an ordinary room temperature alarm in connection with heating systems indicating excessive heat.

Particular attention is called to the specific construction of the sheet metal support which is designed to support the elements of the device of the invention in proper operative relationship to insure durability and efficiency in operation.

It is thought that the description taken in connection with the drawings enables a clear understanding of the invention. Therefore, additional description is thought to be unnecessary.

While the preferred embodiment of the invention has been shown and described, it is to be understood that minor changes coming within the field of invention claimed may be resorted to if desired.

I claim:

1. In a structure of the class described, a supporting fixture made up of a pair of companion sections, each section being of sheet metal, one section being bent to form the major portion of an open-ended rectangular housing and a supporting panel, the remaining section being formed with flanges attached to the panel and said first-named section to complete the housing, brackets for mounting the housing on a support

medium connected to said first-named section, an expanding thermostat mounted in said housing, an audible mechanically operated alarm supported on said panel and including alarm releasing means, pushrod means extending from the releasing means through an opening in the housing into the interior thereof, and arranged to be operatively engaged and moved by said thermostat when the thermostat expands.

2. In a structure of the class described, a supporting fixture made up of a pair of companion sections, each section being of sheet metal, one section being bent to form the major portion of an open-ended rectangular housing and a supporting panel, the remaining section being formed with flanges attached to the panel and said first-named section to complete the housing, brackets for mounting the housing on a supporting medium connected to said first-named section, an expanding thermostat mounted in said housing, an audible mechanically operated alarm supported on said panel and including releasing means, push rod means extending from the releasing means through an opening in the housing into the interior thereof and arranged to be engaged and operated by said thermostat when the thermostat expands, said thermostat being formed with a contact and a binding post, and said pushrod being formed with a complementary binding post, and contact engageable for closing a circuit when the thermostat expands.

3. In an alarm structure of the class described, a support including mounting means, a thermostat carried by the support, and an alarm carried thereby, said alarm including a casing having its wall formed with an opening, a bell surrounding the casing, a hammer pivotally mounted in the casing and operable through the opening to strike the bell, a clockworks supported in said casing for operating the hammer, a trip latch 115 for releasing the clockworks into operation, a spring-retumed pushrod operable through the casing, an operative connection between the push rod and trip latch, and an expanding thermostat carried by said support for operatively engaging the push rod when the thermostat expands.

4. In an alarm structure of the class described, a support including mounting means, a thermostat carried by the support, an alarm carried thereby, said alarm including a casing having its wall formed with an opening, a bell surrounding the casing, a hammer pivotally mounted in the casing and operable through the opening to strike the bell, a clockworks supported in said casing for operating the hammer, a trip latch for releasing the clockworks into operation, a spring returned push rod operable through an opening provided in the casing, an operating connection between the push rod and trip latch, an expanding thermostat carried by the said support for operatively engaging and pushing the push rod when the thermostat expands, an electrical contact on the push rod, a second electrical contact on the thermostat for engaging the first contact when the thermostat expands to close an alarm circuit in which the contacts are interlocked.

FRANK H. PIETZSCH.
